UNITED STATES PATENT OFFICE

115,861

DESIGN FOR A FENDER DIRECTION SIGNAL LAMP

William F. Terry, Washington, D. C.

Application June 1, 1939, Serial No. 85,298

Term of patent 7 years

To all whom it may concern:

Be it known that I, William F. Terry, a citizen of the United States, residing at Washington, D. C., have invented a new, original, and ornamental Design for a Fender Direction Signal Lamp, of which the following is a specification, reference being had to the accompanying drawing, forming part thereof.

Figure 1 is a view in side elevation of a fender direction signal lamp embodying my new design; design;

Figure 2 is a side elevational view of the lamp opposite to Figure 1;

Figure 3 is a view in top plan; and

Figure 4 is a view in front end elevation.

I claim:

The ornamental design for a fender direction signal lamp, as shown.

WILLIAM F. TERRY.
